UNITED STATES PATENT OFFICE.

THOMAS A. KILLMAN, OF NASHVILLE, TENNESSEE.

GAME APPARATUS.

Application filed August 10, 1925. Serial No. 49,405.

To all whom it may concern:

Be it known that I, THOMAS A. KILLMAN, a citizen of the United States, residing at Nashville, in the county of Davidson and 5 State of Tennessee, have invented certain new and useful Improvements in Game Apparatus; and I do hereby declare the following to be a full, clear, and exact description of the same, reference being had to the 10 accompanying drawings, forming part of this specification.

This invention relates to improvements in game apparatus and particularly to game apparatus comprising a board having a plurality of spaced fields sub-divided by right angle lines and diagonal lines which intersect to form a number of "crosses" in the fields and a single "cross" or point of intersection in the spaces between the fields, 15 there being a series of "men" or pieces adapted to be moved by participants in the game along the lines from one "cross" to the next adjacent "cross" in an attempt to move such pieces from one 20 field to another, this movement of the pieces of said series being prevented, if possible, by the other participant through means of a single "piece" which, under the rules of the game as played, has the right to 25 jump the other pieces and remove them from the board under circumstances which will hereinafter be more fully described.

More specifically the game comprises a board having three spaced fields arranged in 30 a row, the first field representing Egypt, the next field representing the Wilderness and the third field representing the Promised Land, with a space between the first two fields representing the Red Sea and 35 the space between the second and third fields representing the River Jordan. With the lines laid out as above generally described the series of twelve pieces, representing the Twelve Tribes of Israel, may be 40 moved from cross to cross, in any of the three fields, in an attempt to get them from Egypt to the Promised Land, but in crossing the spaces representing the Red Sea and 45 the River Jordan their movement is restricted to a single "cross" or intersection so that their movement from Egypt to the Promised Land may be effectually prevented by the opposing single piece if the latter is 50 properly used by the participant having 55 control of the same.

With this and other objects in view, the

invention consists in the arrangement and construction of the board as will be herein-after shown and described, and being specifically pointed out in the appended claims. 60

In the drawings,—

The figure represents a plan view of the game board with the men or pieces thereon as they are initially positioned by the participants when the game is to be played. 65

The board 10 which is preferably rectangular may be made of any suitable material and may be of any desired and convenient size. Arranged in a row lengthwise of the board is a plurality of fields preferably also of rectangular shape, these fields 11, 12 and 13 being spaced a short distance from each other. Each field is subdivided by intersecting lines 14 running parallel to the boundaries of the respective fields and by diagonal lines 15 extending at right angles to each other which also intersect one another at the points where the first set of lines 14 intersect. All of the lines 14 terminate at the boundaries of the 70 respective fields with the exception of one of said lines, preferably the line 14^a, located centrally of each of the three fields. This line 14^a it will be observed extends through 75 all three of the fields and through the two spaces 16—17 separating said fields. Likewise, two of the diagonal lines 15^a, of each field, extend into the next adjacent field and intersect each other at the point where they 80 cross the line 14^a, this intersection of the three lines 14^a, 15^a, being located in the 85 spaces 16, 17 between the fields. 90

For playing the game one participant is provided with a series of men or pieces 18 which are initially positioned on the board in field 11 as shown in the drawings and it is his object to move said pieces from one "cross" or intersection to the next "cross" or intersection until said pieces have traversed the lines from their initial position to any of the "crosses" in the field 13. To retard or prevent this movement of the pieces 18 the other participant makes use of a piece 19 which is initially positioned on the "cross" just outside of field 11, as shown in the drawings. In starting the game the person having the pieces 18 makes the first move, the move consisting of moving one of the pieces from a "cross" along one of the lines in any direction to the next adjacent "cross" and each time one of the pieces 18 is moved the opponent can move the piece 19 100 105 110

in an attempt to block the movement of the pieces 18. If one of the pieces 18 should be located on a "cross" next to the piece 19 and the next "cross", beyond the piece 18, that is opposite the piece 19, should be vacant, the piece 19 in making its move can jump the piece 18 into said vacant position, and if the jump should bring him into the same position relative to another piece 18 he can continue his move by making another jump, each piece 18 thus jumped by the piece 19, being considered as captured and immediately removed from the board. In this way piece 19 can capture and remove the several pieces 18 and this system of playing continues until as many of the pieces 18 as possible have entered the field 13 and the piece 19 has captured as many of the pieces 18 as possible.

To add interest to the game it is preferred that field 11 from which the pieces 18 start represent "Egypt"; the space 16 in which the single intersection 20 is located represents the "Red Sea"; the next field 12 represents the "Wilderness"; the next space 17 having a single point of intersection 21 therein represents the "River Jordan"; and, the last field 13 which is the objective of the piece 18 represents the "Promised Land".

In this way the pieces 18 have more or less unrestricted movement while on the portions representing land, but when they are to be moved across those portions representing areas of water it will be seen that their direction of movement is very much restricted. This restriction of movement of the pieces 18 through certain areas, and the rule permitting pieces 19 to capture the pieces 18, offsets the numerical advantages which would otherwise be had by the participant moving pieces 18 over the participant having control of the single piece 19. Following the line of thought suggested by the representations of the fields and spaces the twelve pieces 18 are supposed to represent the Twelve Tribes of Israel and the single piece 19, which seeks to capture them while traveling from Egypt to the Promised Land, represents a Pharaoh.

Additional entertainment can be had from the game if the pieces 18 are numbered so that after the last piece has either entered the Promised Land or been captured and removed from the board the numbers on the pieces 18 captured may be added and scored for the person having the piece 19 while the numbers on the pieces that have entered the Promised Land can be totalled and credited to the participant who has succeeded in getting them into that field. A certain total, say 100, may be fixed upon as the goal and the game can be played such a number of times as is necessary for one or the other of the players to attain a score of 100. In this connection it will be seen that

the game will be quite useful in not only entertaining children but it will also aid in teaching them to add.

While the primary object of the participant having the pieces 18 is to succeed in entering those pieces in the Promised Land or field 13, that participant is also given the right to "block" the piece 19. As an inducement to get the piece 19 to enter a pocket or trap, the person playing the pieces 18 can well afford to sacrifice one or more of his pieces bearing the smaller numbers by moving them into positions where they may be jumped by the piece 19 so that by moving one of pieces 18 after piece 19 has completed its jump the latter will be hemmed in or blocked in a position where he cannot make another move. If the pieces 18 succeed in blocking the piece 19 that particular game is at an end and the numbers on the pieces totalled as before, the total of the numbers on the pieces captured counting for the piece 19 and the total of the numbers of the pieces remaining on the board being credited to the participant having the pieces 18. In view of the difference in value of the various pieces 18 it will be seen that the players must take care not to expose to capture pieces bearing the larger numbers, that is, when a piece 18 is purposely placed in a position to be caught, either to permit advance of another piece or in an attempt to block the piece 19, such purposely-exposed piece should be one bearing a small number. As the piece 19 is subject to being blocked it is not compulsory to jump or capture a piece 18 if such an opportunity presents itself but the matter is discretionary with the player. He can use his judgment as to whether he will capture the man and take a chance of being pocketed or whether he will pass up the opportunity of capturing that man for fear of being pocketed.

What I claim is:

1. A game apparatus comprising a board having a plurality of fields spaced one from the other and each divided by intersecting lines along which pieces are adapted to be moved from one "cross" or intersection to the next adjacent "cross", a plurality of lines of each field extending into the next adjacent field and intersecting each other at a point in the space between said fields to form a single "cross" or intersection in said space, a series of pieces adapted to be moved along any of said lines from one field to another, and a single piece adapted to prevent said movement of pieces from one field to another.

2. A game apparatus comprising a board having a plurality of spaced fields thereon, each field being subdivided by a plurality of lines extending at right angles to each other and diagonal lines extending at right

angles to each other and crossing the intersections of the first set of lines, one of the lines of the first set extending through each of the fields and through the intervening 5 spaces between said fields and two of said diagonal lines of each field extending through one of the intervening spaces into the next adjacent field and intersecting the other line extending through said space, a 10 series of pieces adapted to be moved along said lines from one "cross" or intersection to the next until they have traversed the distance from a field at one edge of the board to the field at the opposite edge, and 15 a single piece movable on said lines and adapted to be used for blocking movement of said series through the restricted lined area in the spaces between said fields.

3. A game apparatus comprising a field 20 representing "Egypt", a second field spaced therefrom representing "The Wilderness"

and a third field spaced from the second representing the "Promised Land", the space between the first and second fields representing "Red Sea" and the space between the second and third fields representing "River Jordan", each field being divided by intersecting lines forming a plurality of "crosses" or intersections in each field and there being a single "cross" or intersection formed in each intervening space by lines extending from the adjacent field, a series of pieces representing the "Twelve Tribes of Israel" adapted to be moved along said lines from one "cross" to the next adjacent "cross" until they have traversed said lines from "Egypt" to "Promised Land" and a single piece adapted to be moved along said lines to prevent such movement of the pieces of said series.

THOMAS A. KILLMAN.
